UNITED STATES PATENT OFFICE.

GUSTAF LAMBERT, OF CHARLOTTENBURG, GERMANY.

TELEPHONE SYSTEM FOR CENTRAL STATIONS.

No. 818,560.

Specification of Letters Patent.

Patented Feb. 27, 1906.

Application filed April 16, 1902. Serial No. 103,123.

To all whom it may concern:

Be it known that I, GUSTAF LAMBERT, electrical engineer, and a subject of the King of Sweden and Norway, residing at 46 Joachimsthalerstrasse, in the city of Charlottenburg, near Berlin, Kingdom of Prussia, and German Empire, have invented a certain new and useful Telephone System for Central Stations, of which the following is a specification.

It is well known that in the installation of telephone central stations of larger size it has frequently been found convenient to arrange the subscriber-circuits in the central station in two or more groups for the purpose of both saving in multiple jacks and cables and also in order to obtain a high efficiency of the central station. The subscribers are for this purpose provided with a signal-lamp, and the terminals of the subscriber-stations are provided with a suitable key for calling up the different groups of the telephone central station. In cities with two or more telephone central stations of larger extent, where the majority of conversations are held on the intercommunication lines and only so many subscriber-circuits need to be arranged in the central station as are contained on a multiple circuit, it is, however, convenient to arrange the subscriber connections in a group and to arrange the leading-off intercommunication connections in one or several separate groups, each subscriber being provided with signaling devices, the number of these signaling devices corresponding to the number of the other stations on the same system. Thus the signal of the subscriber indicates directly with what station he desires to be connected. The operator therefore does not need to inquire; but it is only necessary to establish communication with the desired central station of an intercommunication circuit which is not busy. In consequence of the smaller number of talking-circuits within the central station in this case a larger number of subscriber-circuits may be arranged in the first group upon each operating-table than was ordinarily the case. In the other groups intended for the leading-off intercommunication lines up to thousand circuits may be attended to by the operator.

This invention has reference partly to the last-mentioned arrangement of the lines in separate groups for subscribers and for intercommunication lines, and it refers partly to a switching device particularly suitable for

this purpose and for the first-mentioned arrangement in groups of subscribers in general.

The system and device is shown on the accompanying drawings for a number of four groups.

The subscriber-table *a* is provided with the speaking-key *b*, included on the branch *c* of the subscriber double circuit *c d*, the arrangement being such that by depressing the key *b* the branch *c* of the subscriber-circuit is grounded. By this earth connection the circuit of the battery *e* is closed through the electromagnet *f*, the armature *g* of the electromagnet *h*, contact-piece *z*, the conductor *c*, and the key *b*. The alarm apparatus of the subscriber-table may be arranged in series with a condenser, or it is provided with so large a resistance that the current of the battery *e* does not actuate the electromagnets *f* and *p*, respectively, included upon the conductors *c* and *d* while the telephone is suspended from the hook *o* and the key *b* remains inoperative. Upon depressing the key *b* the electromagnet *f* will attract the armature *i*, pivoted upon the stationary pin *l*. The hook *k*, which is attached to the armature *i* and is rotatable upon the shaft *l*, revolves the wheel *l* and turns the arm *m*, connected therewith, so as to cause the latter to rest against the contact *n*, the holding-dog *q* preventing backward movement of *l*. If the speaking subscriber desires to obtain a connection within the group I, he allows the key *b* to reassume its original position of rest, and he then takes his telephone off from the hook *o*. By this means the two branches of the double circuit *c d* are connected with each other by the medium of the subscriber-table. This results in a series connection of the coils *s t* of the electromagnet *p*, which is shown in full lines, with the electromagnet *f* and upon the circuit of the battery *e*, a circuit being established from one terminal at the battery *e* through the armature *t*, the armature *g*, contact-piece *z*, conductor *c*, subscriber's table, conductor *d*, the contact *s*, the armature *3*, and the coils *s t*, to the other terminal of the battery *e*. Inasmuch as the electromagnet *p* has a very considerable number of convolutions with comparatively high resistance, while the electromagnet *f* has a small number of convolutions with low resistance, the current thus produced will be sufficient only to excite the first electromagnet; but it will refuse to excite the latter elec-

55 11

tromagnet. The armature *g* is attracted, it closes the contact 13, and thereby establishes a local circuit from one terminal of the battery *e* through *r*, the contact *s*, and the armature *t*, the dotted convolutions (6-7) of the electromagnet *p*, the armature *g*, the contact 13, the glow-lamp *u* in the group I, contact *n*, arm *m*, and wheel *l* to the other terminal of the battery. Simultaneously with the contact 13 the contact 2 is closed, and the electromagnet *f* is short-circuited by means of the circuit-closing piece *l*, which is connected to the armature *g* and is insulated therefrom. The local circuit which actuates the armature *g* and the signal-lamp *u* remains closed for a sufficient length of time until the operator of the group I answers to the call by inserting the plug *v* into the jack *w*, even if the hook *o* should be depressed in the mean-
time.

By inserting the plug *v* into the jack *w* the conductor *x* is grounded, thereby closing the circuit of the battery *e* by way of the electromagnets *h* and *y*, arranged in shunt-circuit. The exciting of the electromagnet *h* results in the interruption of the contacts *s* and *z*, thereby cutting out in the first place one of the branches *c* of the two branches *c d* of the double conductor of the speaking subscriber from the switching device, besides the coils 6-7 with the lamp *u* are cut off from the battery *e*. When the electromagnet *y* is excited, the contact 5 is broken in the first place, thus cutting off the coils 8-9 of the electromagnet *p* from the branch *d*. Then the extension of the armature 3 pulls the dogs *k* and 4 away from the wheel *l*, thus releasing the latter and causing the arm *m* to return to its initial position by the action of its own weight. The short circuit with the electromagnet *f* established by the contacts 1 and 2 is for the purpose of preventing any further displacement of the arm *m* by pressure upon the key *b* after the telephone has been taken off the hook or in consequence of the connection to earth which might be established upon the insertion of the plug into the jack *w*. If the speaking subscriber wishes to actuate another of the signal-lamps which belong to his line in another group, it is only necessary to depress the key *b* so many times as the number of the desired group indicates.

What I claim, and desire to secure by Letters Patent of the United States, is—

1. A telephone system comprising two or more groups at the central station which the

subscriber may call up directly and whenever desired, a loop-conductor connected to the telephone central station, one branch of the double conductor-line of the subscriber including an electromagnet *f* at the station, a circuit-closing piece *m* actuated by said electromagnet, so as to assume the calling or signaling position, another electromagnet *p* upon the other branch adapted to be put in connection with the said circuit-closing piece *m*, and a signal-lamp *u* the circuit of which is maintained closed by means of the connections between said electromagnet *p* and said circuit-closing piece until the call is answered from the station, the said signal-lamp being arranged in the answering group.

2. A telephone system comprising a loop-conductor line connected to the central station, an electromagnet *p* in one branch of said loop and an electromagnet *f* on the other branch, a selective means actuated by said electromagnet *f* and means to short-circuit the electromagnet *f* by the actuation of the electromagnet *p* until the call is answered.

3. In a telephone system, comprising a loop-conductor line connected to the central station, substantially as described, and an electromagnet *f* on one branch and an electromagnet *p*, a signal-lamp on the other branch in connection with said electromagnet *p*, an inquiry-plug *v* and two electromagnets *h* and *y* excited by inserting the said plug, the armature of the electromagnet *h* cutting out the subscriber-circuit of the electromagnets *f* and *p* from the signal-lamp, while the armature of the electromagnet *y* causes the circuit-closing piece *m* to return to its initial position and disconnecting the electromagnet *p* from the subscriber-circuit.

4. Telephone system including magnets *p*, *f* and circuit connections, substantially as described, in which the number of convolutions and the resistances of the electromagnets *f* and *p* are so calculated that the circuit generated in the subscriber-table after taking the telephone off its hook, actuates the electromagnet *p* only, but not the electromagnet *f*, and selective means operated by said electromagnets.

In witness whereof I have hereunto signed my name in the presence of two subscribing witnesses.

GUSTAF LAMBERT.
